ELECTRICAL INSTRUMENT FOR DIAGNOSING AND ASSISTING DEFECTIVE HEARING

Application filed July 31, 1928, Serial No. 296,557, and in Germany April 12, 1927.

Our invention relates to electrical instruments for diagnosing and assisting defective hearing.

Sound amplifying instruments for the use of persons afflicted with defective hearing do not operate satisfactorily at an amplification above a certain limit, even if the usual mistake of using the lower acoustic frequencies is avoided, and this is particularly the case with electrical instruments of this type, which amplify the audible sounds practically uniformly over the whole range of frequency, as a limit is soon reached, above which the amplification can not be raised because, although the instruments may work physically in a perfect manner, speech becomes unintelligible, or at least reaches the ear in such a distorted manner, that the attention of the person with the defective hearing is strained to an excessive amount, and he becomes tired out very quickly.

This phenomenon is connected with the fact that in human speech sounds of low frequency possess great energy but are not especially important for understanding whereas the sounds of high frequency, for instance within a frequency range from 1000 to 4000 cycles per second are not so sonorous, but are of the greatest importance for the understanding of speech.

At a certain amplification, which is assumed to be uniform for all audible frequencies, the sounds of low frequencies, in themselves already strong, are brought to the ear in far too great a volume.

This very often causes pain in the middle ear, and subjective combinations and overtones are induced in the ear which confuse and distort the speech, and thereby make it unintelligible, in consequence of the overloading due to the fact that the intensity of the sounds perceived by the ear is not directly proportional to those emitted by the sound conducting apparatus. The sounds of higher frequencies are obscured by the low sounds, they are completely submerged, and just because the high frequency components are essential for a clear understanding, the speech becomes quite unintelligible. To this must be added the noises in the room and

other noises, that generally are also of low frequency, and therefore help to drown the high frequency sound components.

According to the invention the low frequency sounds are choked or throttled (either before or during their amplification by means of the electrical device for assisting defective hearing), such choking or throttling effect starting at a certain frequency, and this effect is increasingly greater as the sound frequency is lower, it being possible to choose arbitrarily, within certain limits the frequency at which the throttling starts. The intensity of the throttling effect may also be adjusted toward the lower sounds, as desired.

This throttling, depending on the frequency, which could be effected in any suitable manner, for instance by acoustic means, is preferably effected by electric means, that is through an aperiodic chain of filters, which are placed in circuit behind the sound receiving microphone and in front of, or under certain conditions, in the electric amplifying device. In consequence of the throttling effect increasing at the lower frequencies, the sounds of lower frequencies are only slightly increased, and the ear will not be strained. The sounds of the high frequencies, especially the essential components are no more submerged, in fact they become slightly overdistinct, so that the speech can be easily understood.

The above mentioned disadvantages of a uniform sound amplification over all audible frequencies, and the advantages of a throttling effect according to the invention are especially pronounced in the case of so called nervous deafness in which the hearing is especially defective in the higher notes. The new, preferably electric instrument may be used not only as a hearing appliance for the deaf, but also for diagnosing defective hearing, in a manner similar to that in which a set of spectacles is used for sight testing, that is the throttling can be variably adjusted so as to find out the adjustment most favorable for intelligible speech.

The invention will now be described with reference to the accompanying drawings. In

Figure 1 the assembly of an electric instrument according to the invention is shown diagrammatically.

Figure 2 shows a chain of filters adapted to be put in circuit between the sound receiving microphone and an electrical amplifying device.

Figure 3 shows curves explaining the working of the chain of filters.

Figure 4 is a diagram illustrating the operation of the filter chain under different conditions.

In Figure 1 *m* denotes the sound receiving instrument, which comes into satisfactory operation with sounds of the highest frequency which are important to the intelligibility of speech, or if desired reproduces these sounds in preference.

The speech currents are led to an aperiodic filter *s* the circuit and preferred electrical dimensions of which are shown in Figure 2. The filter comprises a plurality of condensers (for instance 1 microfarad, and 1/10, 1/100, and 1/1000 of a microfarad respectively) connected in series, while in each of the members 1, 2, 3, 4, of the filter chain a shunt resistance is provided (for instance of 200, 2,000, 20,000 and 200,000 ohms respectively). Any desired number of chain members may be switched in or out by means of suitable switches (not shown). The tension taken from the filter *s*, depending on the frequency, is led to an amplifying device *V* which feeds a telephone *t* which is preferably made especially sensitive to the high sounds and is well damped.

The several capacities and resistances can be so chosen, that the throttling effect starts at a predetermined frequency, and the throttling effect can be increased at will in relation to the low frequencies by increasing the number of chain members. Figure 3, where the abscissæ show the pitch (number of vibrations or cycles) of the sound and the ordinates show the corresponding throttling values on a logarithmic scale, illustrates how the start of the throttling effect depends on the time constant of the chain members and how the increase of the throttling depends, at decreasing frequency, upon the number of chain members.

The full line and the dotted lines show the throttling effect through a chain consisting of a one-member chain for two different time constants, the dot and dash lines show the throttling effect for the same two time constants but through a chain of two members. These curves can however be rounded off by choosing other resistances and capacities for both chain members.

If a valve circuit is used for amplification of the speech currents, wherein the several amplifying valves are coupled with resistances and capacities, then the embodiment shown in Figure 1, wherein the chain of fil-

ters *s*, arranged separately from the amplifying device *V*, can be combined with the valve amplifier. The several valves are in the case of the so called resistance amplifier connected together by means of individual chain members which are in principle designed in the same way as the individual members of the filter chain, shown in Figure 2.

Instead of dimensioning, as is usual, the capacities and resistances in such a manner that a practically uniform amplification results over the whole frequency range of the audible sounds, they are so chosen, according to the invention, that a throttling effect results in the manner represented by the curves of Figure 3.

The members of the filter need not necessarily be designed according to Figure 2, but may for instance also contain self-inductances, but so connected and of such dimensions that the individual members do not constitute a slightly damped oscillating circuit, as these might be excited to oscillation by the several sounds of the speech to be amplified, and the equalizing process might have a deleterious effect on the intelligibility of the speech transmission.

The diagram Fig. 4 illustrates the relationship between the pitch of the sounds (abscissæ) and the ratio (ordinates) between output voltage and input voltage, for several different circuit arrangements of the filter chain. Curve *a* shows the condition obtaining when only the first member 1, of the chain is included in the circuit, curve *b* illustrates the condition resulting upon the inclusion of both chain members 1 and 2 in the circuit, curve *c* shows the condition obtaining when the three chain members 1, 2, and 3 are included in the circuit, and curve *d* illustrates the condition resulting upon the inclusion of all four chain members 1, 2, 3, and 4 in the circuit.

It is of course evident that all other parts of the device, such as the receiving microphone and the telephone, must be damped as much as possible.

We claim:

1. In an electrical instrument for acoustic purposes, one or more aperiodic filter members which consist of condensers in the main circuit and of resistances in the coupled branch circuits, and which are so dimensioned that they attenuate the sounds of lower frequency, and a receiving microphone, which, independently of the throttling transmission arrangement, selects the sounds of high frequency for reproduction.

2. In an electrical instrument for acoustic purposes, one or more aperiodic filter members which consist of condensers in the main circuit and of resistances in the coupled branch circuits, and which are so dimensioned that they attenuate the sounds of lower fre-

quency, and a receiving microphone, which, independently of the throttling transmission arrangement, selects the sounds of high frequency for reproduction, and a high tuned and especially well damped telephone.

5 3. In an electrical instrument for acoustic purposes, one or more aperiodic filter members employed as a coupling between the amplifying valves of a resistance amplifying circuit which consists of condensers in the main circuit and of resistances in the coupled branch circuits, and which are so dimensioned that they attenuate the sounds of lower frequency.

10 4. An electrical instrument for acoustic purposes, comprising a transmitter, an adjustable electrical device, which throttles the audible sounds from a predetermined limit frequency in a ratio increasing towards low frequencies, and a receiver to translate the

20 electrical waves into sound waves.

25 5. An electrical instrument for acoustic purposes, comprising a transmitter, an adjustable electrical throttling device operating as an aperiodic filter and consisting of condensers in the main circuit and of resistances in the coupled branch circuits, dimensioned to attenuate the sounds of lower frequency, and a receiver to translate the electrical waves into sound waves.

30 In testimony whereof we affix our signatures.
